MERCHANDISING DISPLAY STAND FOR WRITING INSTRUMENTS AND THE LIKE

Charles S. Brand, 19 Steele Hill Road,
Old Westbury, N.Y. 11568

Filed Oct. 23, 1968, Ser. No. 14,137

Term of patent 14 years

Int. Cl. D6—01

U.S. Cl. D80—9

FIG. 1

FIG. 2

FIG. 3

FIG. 6

FIG. 5

FIG. 4

FIG. 1 is a front elevational view of the merchandising display stand embodying my new design;

FIG. 2 is an elevational view taken from one side thereof;

FIG. 3 is a top plan view thereof;

FIG. 4 is a rear elevational view;

FIG. 5 is an elevational view taken from the side opposite that shown in FIG. 2; and

FIG. 6 is another side elevational view showing the writing instrument display trays in their retracted position.

I claim:

The ornamental design for a merchandising display stand for writing instruments and the like, as shown and described.
